UNITED STATES PATENT OFFICE.

HENRY B. BABSON, OF CHICAGO, ILLINOIS, ASSIGNOR TO PINE TREE MILKING MACHINE COMPANY, OF CHICAGO, ILLINOIS, A CORPORATION OF ILLINOIS.

DESIGN FOR A MILK-PAIL COVER.

53,109.

Specification for Design.

Patented Mar. 25, 1919.

Application filed January 11, 1919. Serial No. 270,747. Term of patent 14 years.

To all whom it may concern:

Be it known that I, HENRY B. BABSON, a citizen of the United States, residing at Chicago, in the county of Cook and State of Illinois, have invented a new, original, and ornamental Design for Milk-Pail Covers, of which the following is a specification, reference being had to the accompanying drawing, forming a part thereof.

Figure 1 is a perspective view, and Fig. 2 is a side elevation of a milk pail cover illustrating my new design.

I claim:—

The ornamental design for a milk pail cover, as shown.

HENRY B. BABSON.
